UNITED STATES PATENT OFFICE

MAX FRIEDLANDER AND WILLIAM T. BAKER, OF SAN FRANCISCO, CALIFORNIA

BEACH COT

Application filed August 9, 1930. Serial No. 474,210.

Our invention relates to improvements in beach cots and the like wherein a foldable cot frame is provided with a cover having an extension engaged by a canopy frame detachably mountable upon the cot frame to hold said extension in an extended position and thereby form a canopy over one end of the cot, said cover also having side extensions movable to raised positions to form wind-breaks along the sides of the cot whereby a person reclining upon the cot may be partially sheltered.

The primary object of our invention is to provide an improved beach cot.

Another object is to provide an improved folding cot having a foldable canopy extendible to form a shelter over the head of a person reclining upon the cot.

A further object is to provide an improved folding cot having extensions movable to extended positions affording partial shelter along the sides and at one end of the cot.

Another object is to provide an improved device of the character described which may be quickly and easily folded or extended, as desired.

A further object is to provide an improved folding canopy frame attachable upon a cot frame to support a canopy over one end of the cot, the several members of the frame being foldable compactly into proximate parallel relation and being extendible to form a rigid frame.

A further object is to provide an improved frame having means to rigidly secure the members in extended operative relation upon a cot frame.

A still further object is to provide an improved device of the character disclosed which may be folded compactly and which may be extended to form an attractive and efficient cot affording partial shelter to a person reclining thereon.

We accomplish these and other objects by means of the improved device disclosed in the drawings forming a part of the present application, wherein like characters of reference are used to designate similar parts throughout the specification and drawings, and in which—

Fig. 1 is a perspective view of our improved beach cot, a portion of the cover being broken away to show the frame structure;

Fig. 2 is a side elevation, partly in vertical section, of the cot;

Fig. 3 is an end elevation of the cot, the cover being shown in vertical transverse section;

Fig. 4 is an elevation of the cross member for the foot end of the cot;

Fig. 5 is a broken detail, partly in section, showing the manner in which a cross member and upright engage the cot frame;

Fig. 6 is a broken detail, partly in section, showing the manner in which the spreader member engages the uprights; and

Fig. 7 is a broken detail, partly in section, showing the manner in which the brace members engage the cot frame.

Referring to the drawings, the numeral 1 is used to designate the side frame members of a folding cot provided with foldable legs 2 pivoted thereon and provided with a fabric cover 3 secured upon the cot frame and foldable therewith. The cot frame structure illustrated is of old and well known construction and forms no part of the present invention other than as associated with and cooperating with the novel elements herein disclosed to produce a new and improved beach cot.

The cover 3, as embodied in our present invention, is provided with an extension 4 upon the head end of the cot, said extension extending longitudinally from the end of the cot and being arranged to form a canopy over the head end of the cot as hereinafter more fully explained. The cover 3 is also provided with side extensions 6 extending laterally from the sides of the cot, preferably along the full length thereof. The extensions 6 are provided with widened portions 7 at the head end of the cot.

A canopy frame is detachably mounted upon the cot frame at the head end thereof, said canopy frame comprising a cross member 8 having openings 9 arranged to engage pins 11 at the ends of the cot frame members 1 to secure the members 1 in spaced relation when the cot frame is extended to operative

position in the ordinary manner, said cross member being mounted in the place of the ordinary end spreader commonly provided for cots of the general type illustrated.

5 The cross member 8 is provided with upright members 12 pivotally connected to the ends thereof by hinge members 13 secured upon the lower ends of said uprights 12. The hinge members 13 are provided with offset portions 14 pivoted to the ends of the member 8 whereby the uprights may be swung from a normal upright position with their ends abutting against the member 8, as shown in full lines in Fig. 3 of the drawings, to a 10 folded position in proximate parallel relation to said member 8, as indicated in dotted lines in said figure. The hinge members 13 are preferably arranged as shown in Fig. 3 whereby one of the uprights may be swung 15 downwardly onto the top of the cross member 8 while the other upright is swung around the end of the cross member and against the under side of said cross member, as indicated, whereby the free ends of the uprights may 20 overlap upon opposite sides of the cross member. The hinge members 13 are provided with apertures 16 arranged to register with the openings 9 of the cross member 8, when the uprights 12 are moved to extended position, whereby the pins 11, engaged by the 25 openings 9, will extend through the apertures 16 and thereby lock the uprights in operative upright position.

30 Arms 17 are hingedly connected to the tops of the upright members 12 by means of hinge members 18 similar to the hinge members 13, said hinge members being pivoted to the tops of the uprights and secured to the arms 17. The arms 17 are of approximately the same 35 length as the upright members 12 and are movable from a folded position in proximate parallel relation to the upright members, as indicated in dotted lines in Fig. 2 of the drawings, to an extended position with the 40 adjacent end of the arm abutting against the upright, as indicated in full lines in said figure, the arms 17 extending toward the foot end of the cot, preferably substantially parallel to the side members 1 of the cot frame. The 45 hinge members 18 are provided with apertures 19 movable to register with recesses 21 formed in the upper ends of the uprights 12 to receive pins 22 upon the ends of a spreader 23 arranged to engage and hold the upper 50 ends of the uprights in spaced relation, the hinge members being locked by said pins to 55 secure the arms 17 in extended operative position.

60 Braces 24 are hingedly connected to the free ends of the arms 17 by means of hinge members 26 similar to the members 13 and 18. When in extended position, the ends of the braces are arranged to abut against the under sides of the arms 17 and to extend 65 downwardly therefrom to engage the side

members 1 of the cot frame. Pins 27 upon the free ends of the braces 24 engage recesses 28 formed in the frame members 1 to secure the braces in operative relation to the cot frame. The braces 24 are arranged to be swung around the ends of the arms 17 and into folded position against the sides of arms 17 which are uppermost when in operative extended position, the braces being movable with the arms 17 to folded position against the uprights 12, as indicated in dotted lines in Fig. 2. The braces 24 and arms 17 when thus folded against the uprights, are movable with said uprights to folded position against the cross member 8, as indicated in dotted lines in Fig. 3.

70 A cross member 29 similar to the member 8 is arranged to detachably engage the ends of the side members 1 at the foot end of the cot. Uprights 31 are hingedly connected to the ends of the members 29 by hinge members 32, similar to the hinge members 13, as shown in Fig. 4 of the drawings, the uprights being pivotally movable from inoperative folded positions, as indicated in dotted lines in said figure, to operative upwardly extending position with the lower ends of the uprights abutting against the upper side of the cross member 29, as indicated in full lines in said figure. The hinge members 32 are provided with apertures 33 matching with recesses 90 formed in the ends of the cross member 29 to engage pins carried by the ends of the cot frame members 1 when in extended position whereby the uprights may be locked in operative positions, as above described with respect to the uprights 12.

75 The cover 3 is preferably provided with a pocket 34 along the juncture of the extension 4 with the end of the body portion of the cover whereby the cover may be engaged by the cross member 8. The foot end of the cover 3 is similarly provided with a pocket 35 to receive the cross member 29.

80 The extension 4 is arranged to be extended upwardly to the top of the canopy frame and then forwardly across the top of said frame, as shown in the drawings, the extreme end of the extension 4 preferably being allowed to hang freely across the front of the canopy. Suitable fasteners 36 are mounted upon the extension 4 to engage corresponding fastening means 36' mounted upon the ends of the arms 17 whereby the extension may be secured in extended position.

85 The side extensions 6 are provided with pockets 37 at the foot end of the cot to receive the uprights 31 whereby said side extensions may be supported in raised position to form a wind break, as shown upon the remote side in Figs. 1 and 2. The widened portions 7 of the extensions 6 are provided with suitable fasteners 38 arranged to engage corresponding fastening means 39 mounted upon the outer sides of the arms 17 where- 90

by said extensions may be secured to the arms 17 to close the sides of the canopy formed by the extension 4.

To set up our improved cot, the cot frame and cover is moved to extended operative position, in the usual manner. The member 8 is then inserted through the pocket 34, the upright 12, with the arm and brace folded into parallel relation thereto and folding against the under side of the member 8, being first moved to substantially longitudinal alinement with the member 8. After the member 8 has been thus inserted, the uprights are swung upwardly to operative extended position, and the member 8 is moved to engage the pins 11, said pins extending through the apertures 16 and into the recesses 9 to lock the uprights in operative position. The arms 17 are then swung outwardly and the braces moved to operative position with the pins 27 engaging the recesses 28, thereby rigidly supporting the arms 17 in extended position. The spreader 23 is then mounted to engage the upper ends of the upright and hold the same in spaced relation, the pins 22 engaging the apertures 19 to lock the arms 17 in extended position. With the canopy frame thus secured upon the cot frame, the cover extension 4 is drawn over the frame and secured by the fasteners 36.

The cross member 29 is inserted through the loop at the foot end of the cot with one of the upright members 31 inserted into the pocket 37 of the adjacent side extension 6, the arm being swung upwardly and secured in upright position as the member 29 is moved to engage the ends of the cot frame members 1. The widened portion of the side extension is then secured to the canopy frame by the fasteners 38, and 39, thereby closing the side of the canopy. If desired, both side extensions may be raised to extended position, but one of the extensions is ordinarily allowed to hang freely, as shown in Figs. 1 and 2 of the drawings.

In operation, the canopy affords a shelter at the head of the cot whereby a person reclining upon the cot may keep the head shaded and protected from direct exposure to the sun's rays. The side extensions 6, raised to operative position, form a wind-break whereby the person may be protected from wind. In this manner, persons may recline in a restful position, and by positioning the cot in accordance with the direction of the wind and the inclination of the sun's rays, a partial shelter is obtained whereby persons may expose their bodies to the sunshine without exposure to the wind, and at the same time protecting their faces from sun burn.

When folded, the arms 17 and braces 24 fold with the uprights into compact relation, thereby permitting the canopy frame to be compactly wrapped with the folded cot

when the device is to be transported from one place to another.

While we have illustrated what we regard as the preferred embodiment of our invention, the device is, of course, subject to modification in numerous details of construction and arrangement. The specific form and shape of the several parts may likewise be modified in various ways to alter the design and appearance of the canopy as desired. We therefore do not wish to be restricted to the specific details illustrated and described, but desire to avail ourselves of all modifications which may fall within the scope of the appended claims.

Having thus described our invention, what we claim as new and desire to secure by Letters Patent is:

1. A beach cot comprising a foldable frame; a fabric cover mounted upon the frame; an extension formed upon one end of the cover and extendible to form a canopy over one end of the cot; side extensions formed along the sides of the cover; loops formed in the cover at the ends of the frame; and members insertible through the loops to detachably engage the ends of the cot frame and provided with foldable arms to engage and hold the cover extensions in raised operative positions.

2. A beach cot comprising a foldable frame; a fabric cover mounted upon the frame; an extension formed upon one end of the cover and extendible to form a canopy over one end of the cot; a loop formed at the juncture of the extension with the cover; and a member insertible through the loop to detachably engage the cot frame to hold the frame and cover extended and provided with foldable arms hingedly connected to the ends of the member to engage and hold the extension in extended operative position.

3. A beach cot comprising a foldable frame; a fabric cover mounted upon the frame; an extension formed upon one end of the cover and extendible to form a canopy over one end of the cot; a loop formed at the juncture of the extension with the cover; and a member insertible through the loop to detachably engage the end of the cot frame to hold the frame and cover extended, said member being provided with a plurality of hingedly connected arm portions pivotally connected to the ends of said member and movable to proximate parallel relation in folded position and extendible to angular relation to each other to form a canopy frame engaging and holding the canopy in extended position.

4. A beach cot comprising a foldable frame; a fabric cover mounted upon the frame; an extension formed upon one end of the cover and extendible to form a canopy over one end of the cot; a loop formed at the juncture of the extension with the cover; a

- member insertible through the loop to detachably engage the end of the cot frame, said member being provided with a plurality of hingedly connected arm portions pivotally connected to the ends of said member and movable to proximate parallel relation in folded position and extendible to angular relation to each other to form a canopy frame engaging and holding the canopy in extended position; a second loop formed at the opposite end of the cover; extensions formed upon the sides of the cover; and a cross-member insertible through said second loop to detachably engage the adjacent end of the cot frame and provided with arms hingedly connected to the ends of said cross-member to engage and hold the side extensions in raised operative positions to form a wind-break.
5. A beach cot comprising a foldable frame; a fabric cover mounted upon the frame; an extension formed upon one end of the cover and extendible to form a canopy over one end of the cot; and a canopy frame detachably mountable upon the end of the frame to engage and hold the canopy extensions in extended position, said canopy frame comprising a bar engaging the ends of the side members of the cot frame; uprights hingedly connected to the ends of said bar and foldable to proximate parallel relation thereto; arms hingedly connected to the free ends of the uprights, said arms being foldable to proximate parallel relation to said uprights and being extendible to positions angularly disposed relative to said uprights; and braces hingedly connected to the free ends of the arms, said braces being foldable to proximate parallel relation to said arms and being extendible to engage the cot frame and support the arms in spaced relation to said cot frame.
6. A beach cot comprising a foldable frame; a fabric cover mounted upon the frame; an extension formed upon one end of the cover and extendible to form a canopy over one end of the cot; a canopy frame detachably mountable upon the end of the frame to engage and hold the canopy extension in extended position, said canopy frame comprising a bar engaging the ends of the side members of the cot frame; uprights hingedly connected to the ends of said bar and foldable to proximate parallel relation thereto; arms hingedly connected to the free ends of the uprights, said arms being foldable to proximate parallel relation to said uprights and being extendible to positions angularly disposed relative to said uprights; and braces hingedly connected to the free ends of the arms, said braces being foldable to proximate parallel relation to said arms and being extendible to engage the cot frame and support the arms in spaced relation to said cot frame; and a spreader

detachably mountable between the upper ends of the uprights.

7. The combination with a folding cot frame, of a foldable canopy frame detachably mountable upon the cot frame, said frame comprising a cross member to detachably engage one end of the cot frame; uprights hingedly mounted upon the ends of the cross member; arms hingedly mounted at one end upon the upper ends of the uprights and braces hingedly connected to the free ends of the arms, said uprights, arms, and braces being foldable to proximate parallel relation to each other and to the cross member.

8. The combination with a folding cot frame, of a foldable canopy frame detachably mountable upon the cot frame, said frame comprising a cross member to detachably engage one end of the cot frame; uprights hingedly mounted upon the ends of the cross member; arms hingedly mounted at one end upon the upper ends of the uprights; braces hingedly connected to the free ends of the arms, said uprights, arms, and braces being foldable to proximate parallel relation to each other and to the cross member; and means to hold the uprights in extended upright position when the cross member is mounted upon the cross frame.

9. The combination with a cot frame having outwardly extending pins upon the side members of the frame, of a canopy frame detachably mounted upon said cot frame and comprising a cross member having openings to detachably engage the pins; a pair of uprights; hinge members secured to the uprights and provided with offset portions pivoted to the ends of the cross member, said hinge members having apertures movable to register with the openings in the cross member and engage the pins to secure the uprights in extended positions; arms provided with hinge members pivoted upon the upper ends of the uprights and braces pivoted upon the arms and movable to engage the cot frame to support the arms in spaced relation thereto.

10. The combination with a cot frame having outwardly extending pins upon the side members of the frame, of a canopy frame detachably mounted upon said cot frame and comprising a cross member having openings to detachably engage the pins; a pair of uprights; hinge members secured to the uprights and provided with offset portions pivoted to the ends of the cross member, said hinge members having apertures movable to register with the openings in the cross member and engage the pins to secure the uprights in extended positions; arms provided with hinge members pivoted upon the upper ends of the uprights; braces pivoted upon the arms and movable to engage the cot frame to support the arms in spaced relation thereto; and a spreader detachably engaging

the upper ends of the uprights, said spreader engaging the arm hinge members to secure said arms in extended positions.

In witness whereof, we hereunto set our signatures.

5
